FIG. 1.

INVENTOR.

William Gorman.

FIG. B 2.

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,733, dated November 2, 1869.

DESIGN FOR A BUT-HINGE.

The Schedule referred to in these Letters Patent and making part of the same.

To all whom it may concern:

Be it known that I, WILLIAM GORMAN, of New Britain, in the county of Hartford, and State of Connecticut, have invented and produced a new and original Design for But-Hinges, of which the following is a description, reference being had to the drawings hereunto annexed.

Figure 1 represents the face side of the but, and Figure 2, the reverse side of the same.

A represents a raised border, extending around the edge of each member of the but, giving the effect of a sunken panel to the portion thus surrounded. The ground-work of the panel is matted; raised in relief thereon is an ornamental figure, arranged in equal and similar sections, united in the middle by a beaded band.

B and C are conical tips, ornamented with raised

lines, drawn longitudinally, between which are arranged, alternately, beaded strips and scroll leaves.

The small ends of these tips are ornamented by a knob, which is composed of five united balls or beads. Upon the reverse side of the but, as shown in fig. 2, is a sunken panel, on that portion of the but which will project when the same is properly secured to the door.

This panel is also finished with mat-work, and contains, in relief, a figure corresponding in its general character with those already described.

I claim, as my own invention, the design for a but-hinge, as herein shown and described.

WILLIAM GORMAN.
